[57] CLAIM

The ornamental design for a vehicular running board, as shown and described.

DESCRIPTION

FIG. 1 is a perspective view showing a first embodiment of the vehicular running board installed on a typical vehicle which is shown in broken lines.

FIG. 2 is an enlarged top perspective view of the embodiment of the vehicular running board shown in FIG. 1.

FIG. 3 is an enlarged bottom perspective view of the embodiment of the vehicular running board shown in FIG. 1.

FIG. 4 is a top perspective view of a second embodiment of the vehicular running board.

FIG. 5 is a bottom perspective view of the embodiment of the vehicular running board shown in FIG. 4.

FIG. 6 is an enlarged fragmentary perspective view of one end of the vehicular running board showing a typical tread pattern in broken lines for illustrative purposes only.

FIG. 7 is a perspective view showing the vehicular running board of FIG. 4 on a reduced scale installed on a typical vehicle which is shown in broken lines.

The broken lines in the drawings, representing the vehicle and the tread pattern, are for illustrative purposes only and form no part of the design.
